(57) **CLAIM**

The ornamental design for an indoor data cable wall outlet cover, as shown and described.

DESCRIPTION

FIG. 1 is a back horizontal perspective view of an indoor data cable wall outlet cover in accordance with my new design.

FIG. 2 is a back vertical perspective view of the indoor data cable wall outlet cover of FIG. 1.

FIG. 3 is a top view of the indoor data cable wall outlet cover of FIG. 1.

FIG. 4 is a bottom view of the indoor data cable wall outlet cover of FIG. 1.

FIG. 5 is a left side view of the indoor data cable wall outlet cover of FIG. 1; the right side is a mirror image of the left side.

FIG. 6 is another back vertical perspective view of the indoor data cable wall outlet cover of FIG. 1.

FIG. 7 is a back view of the indoor coaxial/internet cable wall outlet cover of FIG. 1.

FIG. 8 is another back horizontal perspective view of the indoor data cable wall outlet cover of FIG. 1.

FIG. 9 is a front vertical perspective view of the indoor data cable wall outlet cover of FIG. 1.

FIG. 10 is a front horizontal perspective view of the indoor data cable wall outlet cover of FIG. 1.

FIG. 11 is a front view of the indoor data cable wall outlet cover of FIG. 1.

FIG. 12 is a front view of the indoor data cable wall outlet cover of FIG. 1 as it appears in position on a wall installed with a coaxial/internet cable in accordance with my new design; and,

FIG. 13 is a front view of an alternative embodiment of an indoor data cable wall outlet cover as it appears in position on a wall installed with multiple Ethernet/computer network cables in accordance with my new design.

The broken lines shown represent unclaimed subject matter and form no part of the claimed design.

1 Claim, 5 Drawing Sheets
